UNITED STATES PATENT OFFICE.

JOHN FEHAN, OF BUFFALO, NEW YORK.

LIQUID-DISCHARGE DEVICE.

1,367,773.

Specification of Letters Patent.

Patented Feb. 8, 1921.

Application filed April 8, 1920. Serial No. 372,333.

To all whom it may concern:

Be it known that I, JOHN FEHAN, a citizen of the United States, residing at Buffalo, in the county of Erie and State of New York, have invented certain new and useful Improvements in Liquid-Discharge Devices; and I do declare the following to be a full, clear, and exact description of the invention, such as will enable others skilled in the art 10 to which it appertains to make and use the same.

My invention relates to liquid discharge devices and more particularly to those intended for withdrawing fuel from fuel tanks 15 of automobiles, motor boats and other vehicles, leaving a reserve supply for use in reaching a filling station, after the major contents of the tank have been consumed.

The principal object of the invention is 20 to provide a rather simple and inexpensive device of the class described which may be adjusted from the exterior of the tank to leave different quantities of fuel in reserve; which may be quickly set for withdrawing 25 the reserve supply; which may be used to prevent the discharge of any fuel; and which will at all times draw the fuel from the bottom of the tank so that the reserve supply will not consist merely of low grade fuel, but 30 will be equal in gravity to that before consumed.

Another object is to provide a novel arrangement of parts for holding the fuel discharge tube in adjusted position, for holding 35 the cut-off valve tightly closed, and for compensating for any wear of this valve and its seat.

With the foregoing in view, the invention resides in the novel construction and arrangement of parts hereinafter described 40 and claimed, the descriptive matter being supplemented by the accompanying drawings.

Figure 1 is a vertical section of the device 45 installed on a fuel tank.

Figs. 2 and 3 are horizontal sectional views on the planes indicated by lines 2-2 and 3-3 of Fig. 1.

Fig. 4 is a detail vertical section showing a 50 modified form of construction.

In Figs. 1, 2 and 3 I have illustrated the preferred form of my device and Fig. 4 is devoted to a slight modification which may be used if desired. In the preferred form 55 shown, the numeral 1 designates a vertically disposed guide adapted for mounting

on a fuel tank such as that indicated at 2, said guide having a depending tubular portion 3 and a liquid outlet 4 above said tubular portion. A liquid discharge tube 5 is 60 slidable vertically in the guide 1 and discharges into said guide, and by means of a stem 6 or any other preferred operating means, said tube may be vertically adjusted from the exterior of the tank to position its 65 lower end at any one of a number of levels, and thus any desired quantity of fuel may be left in the bottom of the tank as a reserve supply.

In addition to the features above briefly 70 mentioned, I prefer to provide means operable by predetermined movement of the tube 5, for cutting off the discharge of liquid through said tube. A preferred form of this cut-off means, together with the most 75 desirable details for the other features of construction, are shown in the drawings, but it is to be understood that numerous modifications may be made.

The guide 1 as shown, consists of an upper 80 section 7 and the tube 3 which depends from said section. The section 7 is by preference of cylindrical form and is threaded at 8 through a collar 9 secured on the fuel tank 2. The upper end of the section 7 is provided 85 with a head 10 and a sleeve 11 is clamped between said collar and head, such sleeve carrying the outlet 4 which is shown in the form of a pipe or tube. Suitable gaskets 12 are interposed between the sleeve 11 90 and the parts 9 and 10 to establish a fluid tight connection and it will be seen that by loosening the contact of the head 10 with the upper gasket, the sleeve 11 may be swung around to position the tube 4 at the most desirable angle. Turning the section 7 to re-thread it into the collar 9, will again frictionally bind the sleeve in place.

The section 7 of the guide 1 is provided with an external circumferential channel 100 13 with which the outlet 4 communicates, and into which the upper end of a bore 14 discharges by way of one or more openings 15. The bore 14 extends from the bottom of the section 7 to a point adjacent the channel 13, and the lower end of said bore is preferably flared to form a conical valve seat 16. Above the bore 14 and in vertical alinement therewith, the section 7 is provided with an appropriate stuffing box 17, and it is through 110 this stuffing box that the stem 6 passes slidably for the purpose of adjusting the liquid

discharge tube 5. The stem 6 is spaced from the wall of the bore 14 in order to permit the passage of fuel between the two and I have shown the lower end of said stem 5 provided with a cone-valve 18 for co-action with the seat 16 to cut off the discharge of liquid whenever desired. Below the valve 18, the stem 6 is provided with a piston 19 10 slidable within the tube 3 and having suitable piston rings 20 contacting with said tube. The piston 19 is provided with a vertical bore 21 which discharges through openings 22 into the tube 3 at a point above the piston, and the upper end of the tube 5 is 15 secured in said bore 21.

For the purpose of holding the stem 6 and consequently the tube 5 in adjusted position, any means may be employed, but I prefer to use a vertical post 23 rising from the 20 head 10, and a spring-pressed detent 24 carried by the aforesaid stem to co-operate with recesses 25 formed in said post. This detent also co-acts with an oblique cam surface 26 at the upper end of the post 23 when the 25 stem 6 is raised to close the valve 18, and the action of the detent on this cam surface, serves to hold the valve tightly closed. The surface 26 is of considerable length so that it may actively co-operate with the detent 20 24, even though the valve and valve seat may be worn to such an extent as to permit upward movement of the stem 6 to a greater extent than when the device was first used. The recesses 25 are positioned wherever required and by setting the stem 6 so that the 35 detent 24 engages with these recesses, the lower end of the tube 5 may be adjusted to numerous levels so that different quantities of fuel will be held in reserve within the 40 tank 2. After the major supply of fuel has been exhausted, the stem 6 may be forced downwardly to the maximum, thus positioning the lower end of tube 5 at the bottom of the tank, so that the remainder of the fuel 45 may be withdrawn.

Attention is directed to the fact that the tube 3 preferably extends to a point in close proximity with the bottom of the fuel tank. By this arrangement, regardless of the 50 location of the lower end of the tube 5, all fuel will be drawn from the bottom of the tank as indicated by the arrows in Fig. 1. It is thus insured that a poor grade of fuel shall not be held in reserve, as invariably happens when the fuel is not taken off from the bottom of the tank. The tube in question is 55 preferably provided with air inlet openings 27 which permit air to enter said tube and thus allow the fuel level to fall within the latter as it recedes in the tank 2. These 60 openings are preferably located however so that they are closed by this piston 19 when the tube 5 is lowered to the maximum for exhausting the reserve supply.

65 The lower end of the tube 5 is provided

with a closure 5^a and the side of said tube is formed with an inlet opening 5^b directly above this closure. This arrangement is preferable over an open-ended tube, in view of the fact that when the liquid level reaches 70 the lower end of such a tube, the suction within the same has a tendency to continually draw the liquid upwardly after the level has reached the lower end of the tube, thereby lowering said level to an undesirable 75 extent. It has been found however, that by using a closure such as 5^a and providing a liquid inlet 5^b in the side of the tube, this difficulty is overcome since the line of suction through the inlet is more 80 nearly transverse to the tube than longitudinal with respect thereto.

Any preferred means may be employed for mounting the detent 24 upon the stem 6, but for illustrative purposes I have shown 85 a T-head 28 mounted on said stem with one end shaped to form a guide 29 receiving the post 3, while its other end is closed by a plug 30. The detent 28 is confined in the horizontal part of the head 28 and its actuating spring 31 is located also within said part, with one end bearing against the detent and its other end thrusting against the plug 30.

In Fig. 4 of the drawings, I have shown a 95 modified manner of constructing the upper section 7' of the guide 1. In this view, no sleeve such as 11 surrounds the section 7', but the latter is provided with an internal annular groove 13' into which the upper 100 end of the bore 14' discharges. A suitable opening 4' leads from the channel 13' for connecting with the liquid outlet pipe. This construction is more simple and may in some instances be more desirable than that 105 above described.

By using the several features of construction shown and described, or equivalent structures, a very desirable device will result, and such device is usable to great advantage for holding in reserve a quantity of fuel to be used in reaching a service station or the like after the main supply of fuel in the tank has been exhausted. By 110 adjusting the outlet tube 5, different quantities of fuel may be held in reserve and upon further adjustment of such tube, the reserve supply may be withdrawn. Also, by raising the tube to the maximum, the valve 18 may be closed to prevent the discharge of any fuel whatever. I prefer to provide a suitable cap or casing C for the adjusting and holding means of the stem 6, but such cap or casing may be easily removed when adjustments are to be made. 115

From the foregoing, taken in connection with the accompanying drawings, it will be seen that although my invention is of comparatively simple and inexpensive nature, it will be highly efficient and in every way 120 125 130

desirable. Since probably the best results may be obtained from the details disclosed, such details may be followed if desired, but I wish it understood that within the scope 5 of the invention as claimed, considerable latitude is allowed for making such changes as occasion may dictate.

I claim:

1. The combination with a liquid tank, 10 of a guide mounted on the top of said tank and having a liquid outlet, a liquid discharge tube slideable in said guide and discharging into the latter, and means rising from said tube through said guide for vertically adjusting the former from the exterior of the tank.

2. The combination with a liquid tank, of 20 a guide mounted on the top of said tank, a liquid discharge tube slideable in said guide and projectable to different levels in said tank, and co-acting means on the tube and guide for preventing discharge of liquid through said tube when it is moved to a predetermined position.

25 3. The combination with a fuel supply tank of an engine, of a fuel discharge tube projectable to different levels in said tank, a guide for said tube, a valve and valve seat carried by said tube and guide and co-operative to prevent discharge of liquid through the former, and means rising from said tube through said guide for adjusting said tube from the exterior of the tank.

4. A liquid discharge device for tanks, 35 comprising a guide adapted to be mounted on the tank, said guide having a liquid outlet, a liquid discharge tube slideable in said guide and discharging into the latter, and means rising from the tube through said guide for adjusting said tube from the exterior of the tank.

5. A liquid discharge device for tanks comprising a guide adapted to be mounted on a tank, said guide having a liquid outlet 45 and a stuffing box, a liquid discharge tube slideable in said guide and discharging into the same, and a stem rising from the tube through said stuffing box for adjusting said tube from the exterior of the tank.

50 6. A liquid discharge device for tanks comprising a guide adapted to be mounted on a tank, said guide having a liquid outlet, a liquid discharge tube slideable in said guide and discharging into the same, a stem rising from said tube for adjusting the latter from the exterior of the tank, a post rising from said guide, and co-acting means on said post and stem for holding the latter in adjusted position.

60 7. A liquid discharge device for tanks comprising a guide adapted to be mounted on a tank, said guide having a liquid outlet, a liquid discharge tube slideable in said guide and discharging into the same, a stem rising from said tube for adjusting the

latter from the exterior of the tank, a post rising from said guide and having vertically spaced recesses, and a spring-pressed detent carried by said stem for co-action with said recesses to hold the stem in adjusted 70 position.

8. A liquid discharge device for tanks, comprising a guide adapted for mounting on the tank, said guide having a liquid outlet and a depending tubular portion below said 75 outlet, and a liquid discharge tube having a piston slideable in said tubular portion of said guide, said tube having a liquid outlet opening into said tubular portion above said piston.

80 9. A liquid discharge device for tanks, comprising a guide adapted for mounting on the tank, said guide having a liquid outlet and a depending tubular portion below said outlet, a liquid discharge tube having 85 a piston slideable in said tubular portion of said guide, said tube having a liquid outlet opening into said tubular portion above said piston, and means rising from said piston through said guide for adjusting said piston 90 and said tube from the exterior of the tank.

10. A liquid discharge device for tanks comprising a guide adapted for mounting on a tank, said guide having a liquid outlet and a depending tubular portion below said 95 outlet, a stem passing slidably through the upper end of said guide and having an enlarged lower end forming a piston slideable in said tubular guide portion, said piston having a bore and an opening therefrom 100 into said tubular guide portion, and a liquid discharge tube secured at its upper end in said bore.

11. A liquid discharge device for tanks comprising a guide and means for mounting 105 it on the top of a tank, said guide having a liquid outlet, a liquid discharge tube slideable in said guide and discharging into the same, means rising from said tube to a point above said guide for vertically adjusting said tube, 110 and means operable by predetermined movement of said tube for preventing discharge of liquid from said tube into said guide.

12. A liquid discharge device for tanks comprising a guide and means for mounting 115 it on the top of a tank, said guide having a liquid outlet, a liquid discharge tube slideable in said guide and discharging into the same, means rising from said tube to a point above said guide for vertically adjusting said tube, 120 and a valve and valve seat carried by said tube and guide for co-action in preventing discharge of liquid from said tube into said guide when said tube is adjusted to a predetermined point.

125 13. A liquid discharge device for tanks comprising a guide adapted to be mounted on the tank, said guide having a liquid outlet and a depending tubular portion below said outlet, said guide also having an inter- 130

nal valve seat, a liquid discharge tube having a piston slidable in said tubular guide portion, said tube discharging above said piston, means for vertically adjusting said 5 piston and tube from the exterior of the tank, and a valve movable bodily with the piston for co-action with said valve-seat to prevent discharge of liquid.

14. A liquid discharge device for tanks comprising a guide adapted for mounting on a tank, said guide having a liquid outlet and a depending tubular portion below said outlet, a stem passing slidably through the upper end of said guide and having an enlarged lower end forming a piston slidable in said tubular guide portion, said piston having a bore and an opening therefrom into said tubular guide portion, a liquid discharge tube secured at its upper end in said bore, a valve carried by said stem, and a valve-seat within said guide, said valve and seat being coöperable in preventing discharge of liquid.

15. A liquid discharge device for tanks comprising a guide adapted for mounting on the tank, said guide having a liquid outlet, a stem passing slidably into the upper end of said guide, a liquid discharge tube carried by said stem and slidable in said 25 guide, valve means operable by maximum raising of said stem to prevent the discharge of liquid, a post rising from said guide and having an oblique cam surface, and a spring-

pressed detent carried by said stem for co-action with said post to hold the same in adjusted position, said detent being engageable with said cam surface when raised to close the valve, whereby to hold said valve tightly closed and to compensate for wear.

16. A liquid dispensing device comprising a suction tube insertible to different levels in a tank, the lower end of said tube having a closure and a liquid inlet immediately above such closure, whereby to prevent continued suction of liquid into the tube when the level has reached the lower end of the tube.

17. A liquid discharge device comprising a tubular guide adapted to extend from a point near the bottom of a tank through the top of such tank, said guide having a liquid outlet at its upper end and an air inlet between its ends for disposition within the tank, a liquid discharge tube within said tubular guide having on its upper end a piston contacting with said guide, said liquid discharge tube having a liquid outlet into said guide above said piston, and means rising from said tube to a point above said guide for raising and lowering said tube and its piston, said piston serving to close said air inlet when in its lowermost position.

In testimony whereof I have hereunto set my hand.

JOHN FEHAN.
